US00D775728S

(12) **United States Design Patent** (10) Patent No.: **US D775,728 S**
(45) Date of Patent: ** Jan. 3, 2017

(54) **MEDICAL DEVICE HANDLE**

(71) Applicant: **The Spectranetics Corporation**,
Colorado Springs, CO (US)

(72) Inventors: **Gilberto Cavada**, Wauconda, IL (US);
Martin J. Kimbell, Wauconda, IL (US);
Matthew Errol Zotter, Colorado Springs, CO (US);
Matthew Miles Magee, Monument, CO (US);
Steven Thomas Saville, Monument, CO (US);
Timothy J. Hale, Castle Rock, CO (US);
Jeffery David Payne, Pueblo, CO (US);
Deepa Deepa, Colorado Springs, CO (US)

(73) Assignee: **The Spectranetics Corporation**,
Colorado Springs, CO (US)

(**) Term: **15 Years**

(21) Appl. No.: **29/532,214**

(22) Filed: **Jul. 2, 2015**

(51) LOC (10) Cl. **24-02**

(52) U.S. Cl.

USPC **D24/144**

(58) **Field of Classification Search**

USPC ... D24/144, 146, 133, 165; D13/184; 606/1, 606/32, 41-42, 46, 49, 167; 16/110.1; 81/177.1; 600/131

(57) **CLAIM**

The ornamental design for medical device handle, as shown and described.

DESCRIPTION

FIG. 1 is a front perspective view of a medical device handle illustrating our new design;

FIG. 2 is a front side view thereof;

FIG. 3 is a rear side view thereof;

FIG. 4 is a top view thereof;

FIG. 5 is a bottom view thereof;

FIG. 6 is a left side view thereof; and,

FIG. 7 is a right side view thereof.

The broken lines shown in the figures represent portions of the medical device handle that form no part of the claimed design.

1 Claim, 5 Drawing Sheets
